OVERSHOE

Duncan E. Slade, Naugatuck, Conn., assignor to United States Rubber Company, New York, N.Y., a corporation of New Jersey

Filed Dec. 3, 1965, Ser. No. 38

Term of patent 14 years

(Cl. D7—4)

FIG. V

FIG. 1 is a front perspective view of an overshoe showing my new design;

FIG. 2 is a rear perspective view thereof;

FIG. 3 is a side elevational view;

FIG. 4 is a side elevational view of the side opposite that shown in FIG. 3; and

FIG. 5 is a bottom plan view of the sole portion of the overshoe.

The essential features of my design reside in the portion thereof shown in FIG. 5.

I claim:

The ornamental design for an overshoe, substantially as shown and described.
